(57) **CLAIM**

(21) Appl. No.: **29/351,646**

We claim the ornamental design for a rotatable arm, as shown

(22) Filed: **Dec. 9, 2009**

and described.

(51) **LOC (9) Cl.** 12-16

DESCRIPTION

(52) **U.S. Cl.** D12/195

FIG. 1 is a perspective view of the rotatable arm;

(58) **Field of Classification Search** D12/195,

FIG. 2 is a top view thereof;

D12/400, 401, 404, 406, 412, 414, 222, 223,

FIG. 3 is a left side view thereof;

D12/86, 93, 101; 224/923, 924; 211/100,

FIG. 4 is a front view thereof;

211/124, 2, 4, 85.7; D6/552

FIG. 5 is a right side view thereof;

See application file for complete search history.

FIG. 6 is a rear view thereof; and,

(56) **References Cited**

FIG. 7 is a bottom view thereof.
